CLIP AND EARRING COMBINED

Valentine Martin, New York, N. Y.

Application June 30, 1944, Serial No. 542,874

2 Claims. (Cl. 63—14)

1

My invention relates to clips and earrings combined and has particular reference to articles of jewelry which can be used as earrings or as clips or brooches.

My invention has for its object to provide an article of jewelry having an ornamental body with a hinged clamping member or arm at the rear which is resiliently urged towards the body for clamping an object placed between the body and the clamping arm.

Another object of my invention is to provide means for a secure engagement of an object, such as a garment by the clamping member, for which purpose the clamping member is provided with a sharp pin which can pierce the object thereby firmly retaining the clip on the object.

Still another object of my invention is to provide means to remove the sharp pin or to place the same in an inoperative position when the article is used as an earring. I provide for this purpose a hinged connection between the pin and the clamping arm of the article whereby the pin can be folded out of the way and placed into a corresponding groove in the clamping arm.

Still another object of my invention is to provide interlocking cam-shaped projections and recesses on the clamping member and a post on the body of the article to which the clamping member is hingedly connected, whereby the member is resiliently urged into an operative or clamping position.

Other objects and advantages of my invention are more fully explained in the accompanying specification and drawing in which—

Fig. 1 is a rear view of my combination clip with the clamping arm in a folded or operative position;

Fig. 2 is a side view of the same;

Fig. 3 is a side view of the article with the clamping arm turned into an inoperative position;

Fig. 4 is a top view of the same;

Fig. 5 is a bottom or inside view of the clamping arm;

Fig. 6 is a sectional side view of the clamping arm;

Fig. 7 is a rear view of a modified clip;

Fig. 8 is a fractional end view of the cylindrical portion at the end of the arm showing cam-shaped recesses on an enlarged scale;

Fig. 9 is a similar view of the arm-supporting post;

Fig. 10 is a fractional detail view of a pin on an enlarged scale taken along the section line 10—10 of Figure 5.

2

My clip or earring consists of a main body 1 which may be of any suitable ornamental shape as, for instance, in the shape of a leaf with an ornamental projection or a stone 2 at the top. 5 A hinge post 3 is attached to the rear side of the body 1 by its three legs 4, 5, 6. The post is provided with a central cylindrical portion engaged at the ends by cylindrical portions 7 of resilient legs 8 of a clamping arm 9. A pin 12 pivotally connects the portions 7 with the post 3. The end portion 10 of the clamping arm may be circular and cup-shaped as shown, the convex portion 11 being adapted to engage a portion of a garment such as a lapel for holding the clip in place. To render the engagement of the garment by the convex portion more positive, a sharp pin 15 is provided, hingedly connected with bosses at 16 to the cup-shaped portion 11 by a pin 14. The hinge is placed eccentrically in the 15 portion 11, the central portion being provided with an opening 17 through which the pin 15 may be pushed into an operative position shown in Fig. 3.

The cup-shaped portion 11 is provided with a 20 suitable recess or slot 22 for the end of the pin 15 so that the latter, when folded into an inoperative position as shown in Fig. 6, is concealed by the walls of the slot. The article with the pin folded out of the way can be conveniently 25 used as an earring, the cup-shaped portion 11 being smooth with the pin fully concealed.

The article can be made right and left hand for the use as an earring or it may be of a symmetrical shape as shown in Fig. 7, which shows 30 an octagonal body 20.

The hinge post 3 is provided at the inner sides with cam-shaped projections 18 engaging corresponding recess 19 in the resilient legs 8 of the clamping arm. The projections are so arranged that the clamping arm tends to snap into a lock or operative position shown in Fig. 1 or 7. There may be two sets of the recesses 19 provided in the legs 8, as shown in Fig. 8, at right angles to each other, for causing the clamping 40 arm to stay in an open position as shown in Fig. 3, the post 3 having corresponding recesses 19 as shown in Fig. 9.

The pin 15 is similarly frictionally engaged by the sides of the bosses 16 so that the pin, when 45 opened will tend to stay in that position. Additional resilient prongs 21 may be provided for yieldably retaining the pin in an inoperative position.

It will be understood that various features and 50 principles of each of the embodiments of the in-

vention above described or referred to may be utilized or substituted in the other embodiments.

While the invention has been described in detail with respect to certain particular preferred examples, it will be understood by those skilled in the art after understanding the invention, that various changes and further modifications may be made without departing from the spirit and scope of the invention, and it is intended therefore in the appended claims to cover all such changes and modifications.

What is claimed as new and desired to be secured by Letters Patent is:

1. A clip and earring combined comprising a main ornamental body; a clamping arm hinged-
ly connected at one end to the body; means to
yieldably retain the clamping arm in an opera-
tive position at the body and in an inoperative
position away from the body, at a large angle
to the operative position, the free end of the 20
clamping arm having an opening; and a pin piv-
otally supported on the end of the clamping arm
at one side of the opening for rotation at about
90° in a plane normal to the plane of the head
of the clamping arm, the head of the clamping
arm at a point opposite the hinged base of the
pin having a recess for concealing the end of the
pin; the clamping arm having a recess for the
point of the pin on sides of the recess extending
parallel to the point of the pin.

2. A clip and earring combined comprising a
main ornamental body; a clamping arm hinged-

ly connected at one end to the body; means to
yieldably retain the clamping arm in an opera-
tive position at the body and in an inoperative
position away from the body at a large angle to
the operative position; a cup-shaped head on the
clamping arm having a central opening; bosses
at the inner side of the cup-shaped head; and a
pin having an enlarged base pivotally and fric-
tionally supported between the bosses, the pin
being arranged to be rotated at about 90° in a
plane transverse to the plane of the cup-shaped
head to be placed in an operative position in a
direction toward the body of the clip, the head
having a recess on the outside for the middle por-
tion of the sharp point of the pin when the pin
is placed in an inoperative position, the point
of the pin slightly extending beyond the recess
for moving the pin by the user's finger nail.
